J. M. RUSSELL

PARACHUTE PACK

Filed April 12, 1926

Patented June 7, 1927.

1,631,767

UNITED STATES PATENT OFFICE.

JAMES M. RUSSELL, OF SAN DIEGO, CALIFORNIA, ASSIGNOR TO HERBERT R. MCCLINTOCK, OF SAN DIEGO, CALIFORNIA.

PARACHUTE PACK.

Application filed April 12, 1926. Serial No. 101,420.

This invention relates to parachutes of the type adapted to be worn on the back of an aviator, and the primary object is the provision of a parachute which is retained in a container of novel form and consisting essentially of a face piece of flexible material, having side flaps; and a separate piece, which together with the side flaps, forms one side of the container. A further object is the provision of a parachute container of this type having means extending through the parachute to interconnect the side edges of the separate piece with the edges of the side flaps and with the opposite face of the container on its opposite side.

A further object is the provision of a non-rigid pack which will more or less conform to the body of the wearer, and having the parachute retained in position by means of fastening cones attached to the separate piece, these cones passing through the pack and being fastened to a pull cord adapted to be manually operated by the wearer after he is clear of the aircraft. The separate piece of the container is fixed to the pull cord so that it will be positively removed from its position and freed of the rest of the pack after the pull cord is operated to release the locking cones.

A further object is the provision of a parachute pack of trapezium form, having a smaller top edge than the lower edge and having upwardly converging sides which are substantially parallel to the two adjacent sides of the triangular flap which is separable from the rest of the pack.

Further objects and advantages of my invention will be more fully set forth, reference being had to the following description of the preferred form of my invention, and to the accompanying drawing in which

Fig. 1 is a rear elevation of the side of the pack which is exposed to the slipstream.

Fig. 2 is a front elevation of the pack showing the side which is placed against the wearer's back.

Fig. 3 is a section on the line 3-3 of Fig. 1.

Fig. 4 is a view of the rear of the pack after it has been opened and the separate triangular piece removed, and

Fig. 5 is a view of the ejection strap and pull cord attachment.

Referring more particularly by reference numerals to the drawings, the parachute

pack indicated therein is formed primarily of the face piece of material 1 having a trapezium shape with the top edge 2 thereof substantially shorter than the bottom edge 3, and having two side edges 4 and 5 converging upwardly. Attached to the edge of the face piece 1 are the top flap 6 of substantially triangular form, bottom flap 7 and two side flaps 8 and 9; all of the side flaps extending a short distance towards the center of the pack where they are overlapped by a separate triangular piece 10, the piece 10 overlapping the inner edges 11, 12 and 13 of the three flaps 8, 9 and 7, as shown. The various flaps, face piece 1 and triangular section 10 are all constructed of flexible fabric material which is devoid of rigidifying elements with the exception of the two thin spring pieces 14 which extend vertically along the face 1 and which may take the form of corset steels fastened to the fabric section 1, so that the entire pack will be of a non-rigid and yielding construction. With such a construction the pack may yield and give in the movements of the wearer and will more closely conform to the shape of the body. The pack is adapted to be worn on the back of the aviator with the section 1 against his back, and with the flap 10 exposed to the air-rush. The various flaps fold around and enclose the sustaining parachute 15 which is stuffed into the container in a comparatively loose manner so that the pack will be pliable. It is to be understood that the parachute completely fills the container, although it is preferred that the parachute should not be so tightly pressed into the container as to form a compact mass. The suspension straps 16 of the customary form extend into the pack and are connected to the ropes of the parachute.

Any suitable harness may be used for attaching the pack to the back of the aviator.

Attached to each corner or apex of the triangular flap 10 is an attaching cone, the cones being indicated at 17, 18 and 19. These cones project downwardly into the pack and extend through grommets in the edges of the side flaps, and also through grommets provided within front face or section 1, the cones then projecting out on the opposite side of the pack where they are held in place by a pull wire 20, having branches 21, 22 and 23 which extend through the ends of the cones 17, 19 and 18 respectively. The

branches of the pull wire are located on the forward side of the pack and between the front section 1 and the back of the aviator, and are attached rigidly to the pull ring 24 5 which may be placed in a suitable location on the pack where it may be easily grasped and pulled.

The pull ring 24 is attached to a strap 25 which extends around to the back of 10 the pack on the outside thereof and enters the pack under the edges of the bottom flap 7 and under the lower edge of the triangular flap 10. At this point the strap is provided with a grommet 26 which co-operates 15 with the cone 18. The strap then extends along the front of the pack, close to the front section 1, and is then folded back so as to extend around the portion of the parachute embraced thereby and is attached to 20 the flap 10 in a permanent manner at the point 27. The strap 25 then extends along the triangular flap 10 to a point 28, the end 25 of the strap then extending towards the center of the pack again to completely embrace the portion of the parachute therein.

It will now be understood that the parachute 15 is placed on the front section 1 around and on all sides of the grommets 30, 35 and 38, and the two side flaps 8 and 30 9 are then folded over in place; the top and bottom flaps 6 and 7 being then positioned and the triangular flap 10 and the ejection strap 25 then applied in position so that the locking cones 17 will extend through the 35 grommet 31 in flap 6, grommets 32 in flaps 8 and 9, and grommet 30 in the front section 1. The cone 18 in a similar manner engages the grommet 33, then grommet 26 and in turn grommets 34 and 35. Locking cone 40 19 extends through grommets 36, 37 and 38 in turn. With the ejection strap positioned around and embracing a part of the parachute and interconnecting the pull ring with the triangular flap 10, it will be apparent 45 that when the pull ring is manually jerked by the aviator the pull cord will be released from the end of the locking cones through which they extend and immediately thereafter as the aviator extends 50 his arm, the flap 10 will be jerked out of place and the part of the parachute embraced by the ejection strap will be forcibly pulled out of the container, where it may catch 55 the air and be completely removed as the air catches the parachute and drags upon it.

The location of the locking cones upon the removable flap 10 reduces the chances of interference between the parachute and cones and removes any possibility of the 60 cones causing interference with the removal of the parachute, since the flap 10 which holds them is jerked clear of the rest of the parachute container as soon as the cones are released. The complete 65 removal of the flap 10 from the rest of

the pack insures the opening of the pack and allows the air to immediately act upon the parachute and drag it entirely out of the container. The triangular form of the removable flap 10 co-acts with the trapezium shape of the pack so that the entire center portion of the pack is opened when the flap 10 is removed, and at the same time permits the minimum number of fastening cones to be used. Furthermore the position of these fastening cones at points substantially removed from the edges of the pack and passing entirely through the pack, provides a means to retain the parachute in its position within the pack and prevents the parachute from shifting around therein. 70 75 80 85 90

I am aware that various changes and modifications may be made within the scope of my invention, and do not intend to be limited to the precise construction which has been chosen herein for the purpose of illustration of the preferred embodiment thereof. 95

I claim:

1. In a parachute pack adapted to be worn by an aviator, a container for the parachute made of flexible material and having a face piece and a plurality of side flaps connected to the edges of the face piece, a parachute within the container, a separate piece of material on the opposite side of the parachute from the face piece, said side flaps overlapping the edges of said separate piece, and locking cones releasably holding said separate piece to the overlapping side flaps to retain the parachute enclosed between the face piece, side flap and the separate piece. 100 105 110 115 120 125 130
2. In a parachute pack adapted to be worn by an aviator, a container for the parachute made of flexible material and having a face piece and a plurality of side flaps connected to the edges of the face piece, a parachute within the container, a separate piece of material on the opposite side of the parachute from the face piece, and means releasably holding said separate piece to the side flaps and to the face piece and extending through the pack to retain the parachute enclosed in position between the face piece, side flaps and the separate piece. 115
3. In a parachute pack adapted to be worn by an aviator, a container for the parachute made of flexible material and having a face piece and a plurality of side flaps connected to the edges of the face piece, a parachute within the container, a separate piece of material on the center of the opposite side of the parachute from the face piece having edges overlapped by said side flaps, and means on said separate piece releasably holding said separate piece to the side flaps to retain the parachute en-

closed between the face piece, side flap and the separate piece.

4. In a parachute pack adapted to be worn by an aviator, a container for the parachute made of flexible material and having a face piece and a plurality of side flaps connected to the edges of the face piece, a parachute within the container, a separate triangular piece of material on the opposite side of the pack from the face piece, and locking cones 10 releasably holding the corners of said separate piece to the side flaps and to the face piece and extending through the pack to retain the parachute enclosed in position between the face piece, side flaps and the separate piece.

5. A yielding parachute container for packed parachutes adapted to be worn by an aviator, comprising a flexible face piece 20 having a plurality of side flaps connected to its edges and extending short distances toward the center of the container and adapted to extend around a parachute, a separate piece of flexible material on the same side of the container as said side flaps and overlapping said side flaps at its edges, locking cones fastened to the corners of said separate piece, grommets in the edges of the side flaps and in the said face piece 25 for engagement with said cones and a pull cord for releasably retaining said grommets in engagement with the cones to maintain the parachute in position within the container.

6. A parachute container for packed parachutes adapted to be worn by an aviator, comprising a flexible face piece adapted to be worn against the aviator's back and having a plurality of side flaps connected to its edges and extending short distances toward the center of the container and adapted to extend around a parachute, a separate piece of flexible material on the same side of the container as said side flaps 40 and overlapping said side flaps at its edges, locking cones fastened to the corners of said separate piece, grommets in the edges of the side flaps and in the said face piece for engagement with said cones and a pull cord between the container and the aviator's back for releasably retaining said grommets in engagement with the cones to maintain the parachute in position within the container.

7. A parachute container for packed parachutes adapted to be worn on an aviator's back, comprising a flexible face piece of trapezium shape with the upper edge considerably smaller than its lower edge and having substantially straight side edges, converging towards the top, a plurality of side flaps connected to the edges of the face strip and extending short distances toward the center of the container and adapted to be placed around a parachute, a separate

triangular piece of material on the same side of the container as said side flaps and overlapping said side flaps at its edges and means to releasably hold the said separate piece to the edges of the side flaps.

8. A parachute container for packed parachutes adapted to be worn on an aviator's back, comprising a flexible face piece of trapezium shape with the upper edge considerably smaller than its lower edge and having substantially straight side edges, converging towards the top, a plurality of side flaps connected to the edges of the face strip and extending short distances toward the center of the container and adapted to be placed around a parachute, a separate triangular piece of material on the same side of the container as said side flaps and overlapping said side flaps at its edges, and means on the corners of the said separate piece to releasably hold the said separate piece to the edges of the said flaps.

9. A parachute container for packed parachutes adapted to be worn on an aviator's back, comprising a flexible face piece of trapezium shape with the upper edge considerably smaller than its lower edge and having substantially straight side edges, converging towards the top, a plurality of side flaps connected to the edges of the face strip and extending short distances toward the center of the container and adapted to be placed around a parachute, a separate triangular piece of material on the same side of the container as said side flaps and overlapping said side flaps at its edges and locking cones interconnecting the corners of the separate piece, the edges of said side flap and the opposing parts of the said face piece together to retain the parachute in position within the container.

10. A parachute pack adapted to be worn on an aviator's back, comprising a container of non-rigid form, formed of a flexible face piece of trapezium shape with the upper edge considerably smaller than its lower edge and having substantially straight side edges, converging towards the top, a plurality of side flaps connected to the edges of the face strip and extending short distances toward the center of the container, a separate triangular piece of material having edges overlapping the edges of the side flaps, a parachute enclosed by said face piece, side flap and triangular piece collectively, and means extending through the pack to retain the parachute in position therein and to interconnect the edges of the side flaps, the corners of the triangular flap and the face piece together, and a rip cord adapted to be manually pulled to release the last named means and forcibly remove the said triangular piece from the pack.

11. In a parachute pack adapted to be worn on an aviator's back, a flexible con-

- 1 tainer of flexible material comprising a face piece together, a pull device for releasing piece of trapezium form having a short upper edge, a longer lower edge and two straight side edges converging together 5 toward the upper edge, a triangular top flap, a pair of side flaps and a bottom flap overlapping each other at their corners, and a triangular center piece of material separate from the side flaps and overlapping the 10 edges of the side flaps on the outside thereof, cones on the corners of the triangular center piece extending through the pack and projecting on the opposite side thereof, a pull ring, and a ripcord extending through the cones on the side of the pack which is 15 against the wearer's back.
12. In a parachute pack, a container for the parachute made of flexible material and having a face piece, and a plurality of side 20 flaps extending a short distance towards the center of the pack, a separate piece of material overlapping the edges of the side flaps, means releasably attaching the edges of the side flaps and the separate pieces together, a pull device for releasing said means, and a strap connecting the pull device to one of said pieces to forcibly remove the separate piece from the rest of the pack when the pull device is operated.
13. In a parachute pack, a parachute, a container for the parachute made of flexible material and having a face piece, and a plurality of side flaps extending a short distance towards the center of the pack, a separate 25 piece of material overlapping the edges of the side flaps, means releasably attaching the edges of the side flaps and the separate 30
